US0D1073952S

(12) **United States Design Patent** (10) Patent No.: **US D1,073,952 S**
(45) Date of Patent: ** May 6, 2025

(54) **HEARING AID**

(71) Applicant: **SHENZHEN SHOKZ CO., LTD.**,
Shenzhen (CN)

(72) Inventors: **Sunjie Huang**, Guangdong (CN); **Lei Zhong**, Guangdong (CN); **Chaowu Li**, Guangdong (CN); **Qianwen Nie**, Guangdong (CN); **Chenlu Lou**, Guangdong (CN); **Qingyu Zeng**, Guangdong (CN); **Fengyun Liao**, Guangdong (CN)

(**) Term: **15 Years**

(21) Appl. No.: **35/520,510**

(22) Filed: **Apr. 7, 2023**

(80) **Hague Agreement Data**

Int. Filing Date: **Apr. 7, 2023**

Int. Reg. No.: **DM/228674**

Int. Reg. Date: **Apr. 7, 2023**

Int. Reg. Pub. Date: **Apr. 12, 2024**
